UNITED STATES PATENT OFFICE.

FLORENCE J. HEPPE, OF PHILADELPHIA, PENNSYLVANIA.

MUSICAL INSTRUMENT.

Application filed December 18, 1919. Serial No. 345,786.

To all whom it may concern:

Be it known that I, FLORENCE J. HEPPE, a citizen of the United States, residing in Philadelphia, in the county of Philadelphia and State of Pennsylvania, have invented certain new and useful Improvements in Musical Instruments, whereof the following is a specification, reference being had to the accompanying drawings.

10 The invention relates more specifically to tone reflectors for musical instruments, such as pianos of all styles and types including grand and upright ones of both ordinary standard forms and player type, and the 15 object of my invention is to provide auxiliary reflecting devices which are independent of the sounding board or the sound producing devices, such reflecting devices being disposed according to the principles hereinafter set forth.

As will become apparent from subsequent description, my invention is particularly applicable to upright pianos, either of standard form or to those of the automatic player 25 type. Ordinarily such pianos are so constructed, that the volume and tone of the musical vibrations are, for reasons which will be presently explained, greatly reduced, and impaired.

30 To be more explicit, in its typical form, such a piano usually comprises in addition to the string plate; a sounding board which is located behind said frame, by which forced vibrations are projected; an action 35 by which the strings are vibrated; and in the case of the player type, an intricate playing mechanism. The two latter groups of mechanism occupy positions in front of the string plate within a casing, which is 40 for the most part completely closed at the front so that the audible vibrations of the sounding board must of necessity, come mostly from the back of the instrument. By reason of such construction, a great 45 portion of the sound waves due to the vibrations of the strings and the sounding board are absorbed within the casing.

It is the aim of my invention to use such 50 sound waves and by redirecting them rearwardly to impart greater resonance to the instrument, and to blend them together, to the end that the tonal quality of the instrument is improved. This I accomplish by use of one or more reflecting devices which 55 are disposed within the casing of the instrument, and each of which comprises a

concaved reflecting surface whereby these sound waves are reflected back and forth until redirected toward the sounding board.

Referring to the drawings, Fig. I, is a 60 front elevation of an upright player piano, conveniently embodying my invention.

Fig. II, is a cross sectional view of the same.

The player piano herein shown is of well 65 known construction, and comprises essentially a casing which is comprehensively indicated at 1, having incorporated with it, a key bed 2, and which is closed at the front, above and below said key bed, by the removable panels 3 and 4, respectively. The instrument further comprises a metallic string plate 6, upon which the strings 7, are mounted, and directly behind which the usual sounding board 8, is located. Within 70 the casing, in the space above the key bed 2, are located the action 9, and the automatic playing mechanism 10, whilst the space below said key bed is occupied for the most part, by the suction creating elements 11, whereby the playing mechanism 75 is actuated.

Disposed at different points within the casing 1, at the sides thereof (as distinguished from the front and the back), are 80 a number of reflecting devices, 12, 13, 14, 15, 16, 17 and 18. Each of these devices comprises a concaved reflecting surface 19, whose configuration and location is such as to effect the projection of the sound waves 85 rearwardly toward the sounding board 8.

The devices 14, 15, 16, 17 and 18, while shown only in dotted lines in Figure I are identical in configuration and concavity to the devices 12 and 13 shown in cross-section 90 in Figure II.

In practice the surface 19, may be constructed of material similar to that of the sounding board so as to be capable of independent vibration, but are preferably constructed of a non-vibratory material capable of reflecting instead of absorbing sound waves. These reflecting devices are braced by a number of transverse ribs 20 and may be secured by means of screws or other equivalent means, to any convenient portion of the piano casing. As will be seen from Fig. I, the reflecting device 12, at the top of the casing extends across the entire width of the instrument. This arrangement is 100 not possible at the bottom of the instrument, on account of the space required for 105 110

the actuating treadles 21, for the player mechanism, and for this reason, separate reflecting devices 13 and 14, of lesser length have been provided at this region, one being disposed at each side of the central opening 22, through which said treadles operate. The latter reflecting elements are of the same general construction as the first described, and attachment in this case is effected either with the bottom board 23, of the casing, or with the lower panel 4. The reflecting devices 15, 16, 17 and 18, at the ends of the instrument co-operate with the others in reflecting the sound waves rearwardly toward the sounding board 8. Thus in operation, it will be seen that, when the strings are actuated, the sound waves produced by them, and also the waves from the sympathetic vibrations of the sounding board within the casing, will be reflected by the several reflecting devices as an echo and redirected toward the sounding board. In this way, instead of being absorbed within the casing, such waves that is, both those originating from string vibrations and those reflected from the reflecting devices are blended, one with another with the result that the general resonant quality of the instrument is improved.

30 The reflectors are made so as to be non-vibratory to a minimum extent and to reflect sound waves to a maximum extent. The manner in which a reflector is made to accomplish this object will depend upon the nature of the materials employed and the principles of construction should be selected with a view to making the reflector as rigid as possible, avoiding thin parts or resilient portions which may have a tendency to vibrate. A wooden panel may be used as a reflecting surface provided it is suitably backed up and solidly mounted so as to reduce vibrational tendencies to a minimum. Any metal which is relatively non-resilient may be employed among which metals may be included lead, and if this material is used it should be in the form of thin sheets to avoid the addition of weight.

40 It is pointed out that by reason of the curvature of the reflecting devices the latter may be designed to afford a maximum area of reflecting surface and at the same time be contained within the narrow and limited confines of the instrument casing.

50

The present invention does not necessarily contemplate the concentration of reflected sound waves upon any definite locality of the musical instrument, nor to secure a reflection of sound waves to such an extent 60 that the reflected character of any sound waves could be detected by ear. The object, however, is to secure reflection of sound waves to some extent and the degree of reflection obtained by the apparatus described 65 is sufficient to cause a blending of sound waves within the instrument and a concentration of the sound waves toward the rear of the instrument so that the resonant quality of the instrument is increased.

70 It will be understood, of course, that my invention is not in its broader aspects limited to the exact form and arrangement of reflectors shown, since considerable variation and variety of reflector form and arrangement are possible in the attainment of some of my objects. The forms and arrangements shown are, however, the best at present known to me.

Having thus described my invention, I 80 claim:

1. In a piano the combination with a casing, a string frame therein, and a sounding-board to the rear of said string frame, of a plurality of concave reflectors of minimum 85 vibratory character disposed around the sides, top and bottom of the casing, said reflectors having their reflecting surfaces directed toward the string frame for reflecting sound waves back toward the sounding board.

2. In a piano the combination with a casing, a string frame therein, and a sounding board to the rear of said string frame, of a concave reflector of minimum vibratory 95 character in said casing at one side thereof, with its axis of curvature extending parallel to the sounding-board and its reflecting surface directed generally toward the string frame, and transverse bracing ribs supporting the curved surface of said reflector and securing it to the casing.

100 In testimony whereof, I have hereunto signed my name at Philadelphia, Pennsylvania, this sixteenth day of December, 1919.

FLORENCE J. HEPPE.
